(57) **CLAIM**

The ornamental design for a container-lid assembly, as shown and described.

DESCRIPTION

The new design is applied to a container-lid assembly of the roll-on type, said container being shaped in order to be seated on the lid, in an inverted position when in an inoperative condition. The present container-lid assembly will be illustrated below by the attached drawings, in which: FIGS. 1, 2, and 3 are perspective views of the container-lid assembly taken at different positions;

FIG. 4 is a lateral elevational view of the container-lid assembly of FIGS. 1-3;

FIG. 5 is a similar view to that of FIG. 4, but illustrating the container-lid assembly turned by 90 degrees;

FIGS. 6 and 7 are similar views to those of FIGS. 4 and 5, respectively, but illustrating the container-lid assembly in the exploded condition, in order to illustrate the ball surface portion projecting partially outwardly from the container of the present assembly; and,

FIG. 8 is a bottom plan view only of the container of the container-lid assembly of the previous figures.
